ROD PACKING

Harold Callahan, Tulsa, Okla.

Application June 20, 1946, Serial No. 678,091

15 Claims. (Cl. 286—16)

1

The present invention relates generally to the rod packing art, and more particularly to an improved stuffing box assembly adapted to seal a wellhead casing about the reciprocating polish rod of an oil well pump.

In the pumping of oil wells which have insufficient natural pressure to force the oil to the surface of the ground, numerous specialized problems arise which are not encountered in ordinary pumping operations of a different nature. For example, there are periods in the operation of an oil well pump during which no fluid is in contact with either the polish rod or its packing and hence it is desirable to provide special equipment to lubricate and cool these elements. Again, many of these specialized problems arise from the nature of the oil itself, which constitutes an ever-present fire hazard and which frequently contains microscopic sand as well as other deleterious materials of an abrasive or chemical nature which are extremely harmful to ordinary packings. Still another problem arises from the fact that the pump frequently must be located far down in the well, thus necessitating the use of unusually heavy machinery at the surface of the well for handling the polish rod and its associated parts. This ordinarily takes the form of a walking beam which in operation imposes a certain amount of sidewise motion or lateral thrust upon the polish rod packing.

It is accordingly an important object of the present invention to provide an improved polish rod stuffing box assembly adapted to seal a wellhead casing and to accommodate slight relative lateral movements of a polish rod therein.

Another object of the invention is to provide a polish rod stuffing box embodying a novel packing element having a particular structure and external shape which enable it to be repeatedly adjusted to maintain adequate, even pressure against the polish rod.

A further object is to provide a stuffing box and packing of the type described wherein necessary adjustments of the pressure of the packing element against the polish rod may be expeditiously accomplished by external means.

Another object of the invention is to provide a novel packing element having a variable shape in cross section whereby it may be adjusted numerous times and still maintain a satisfactory seal despite wear due to friction or corrosion.

A still further object of the invention resides in the provision of an improved packing element formed from a strip of alternate layers of fabric and filaments which has been molded un-

2

der heat and pressure into a unitary structure.

Still another object is to provide an improved stuffing box follower embodying a lubrication chamber comprising a spring-pressed wiper element and spout structure for lubricating the polish rod and packing and for reducing fire hazard.

The above as well as other and further objects and advantages of the present invention, 10 together with a more complete understanding thereof, will become more readily apparent to one skilled in the art from a consideration of the following detailed specification taken in conjunction with the accompanying drawings where-

15 in:

Fig. 1 is a front elevation of a stuffing box assembly in accordance with the present invention showing the parts in the relative positions which they occupy after considerable wear of the pack-

20 ing element has taken place;

Fig. 2 is a longitudinal sectional view to an enlarged scale of the stuffing box assembly of Fig. 1 but taken at right angle thereto and showing the parts in their relative positions prior to 25 any substantial wear of the packing element;

Fig. 3 is a top plan view of the stuffing box assembly, the rod being shown in section;

Fig. 4 is a transverse cross-sectional view through the follower taken substantially along 30 the line 4—4 of Fig. 2;

Fig. 5 is a detailed cross-sectional view of the packing element forming an important part of the present invention;

Fig. 6 is a plan view of the spring for holding the wiper in position; and

Fig. 7 is a transverse cross-sectional view of the wiper element per se.

Referring to the drawings and particularly to Figs. 1 and 2 thereof, there is illustrated an improved stuffing box assembly in accordance with the present invention comprising a generally cup-shaped housing 10, a packing element 11, and a generally cylindrical, hollow gland or follower 12. The housing 10 is apertured as indicated at 13 and is provided with a depending skirt portion 14 adapted to be secured to the top of a well casing 15 as by means of threads 16. A polish rod 17 is shown fragmentarily in position in the stuffing box assembly and it will be understood 45 that this polish rod 17 is adapted to reciprocate within the stuffing box during operation of the pump.

As shown in Fig. 1, the follower 12 is provided with a pair of ears 18 and 19 projecting laterally 50 outwardly from its upper portion and includ-

ing apertures near their outer ends for the reception of a pair of elongated bolts 20 and 21, the heads 22 and 23 of which are adapted to be seated in countersunk recesses 24 and 25 formed in the upper surfaces of the ears 18 and 19, respectively. A similarly shaped pair of ears 26 and 27 project laterally outwardly from opposite sides of the housing 10 and are spaced downwardly an appreciable distance below the top surface of the housing 10. The ears 26 and 27 are also apertured in their outer portions to receive the lower ends of bolts 20 and 21 and are further provided with rectangular shaped recesses 28 and 29 in their lower surfaces, receiving the square nuts 30 and 31 which are threaded on the bolts 20 and 21, respectively. The rectangular shaped recesses 28 and 29 are only slightly larger in one dimension than the width of the nuts 30 and 31 and serve to prevent rotation of the latter upon the bolts 20 and 21 when the nuts are seated in said recesses.

The follower 12 is provided at its bottom portion with a pair of horizontal shoulders 32 and 33 (Figure 2) adapted to abut against similar shoulders 34 and 35 formed by a counterbore in the top portion of the packing element 11, and an aperture 35' is formed centrally in the bottom of the follower 12 for the passage of the polish rod 17 therethrough.

From the description thus far, it will be apparent that the two pairs of ears 18-19 and 26-27 together with their associated nuts and bolts 20-21 and 30-31 serve to retain the components of the stuffing box in assembled relation, the packing element 11 and follower 12 being in nested relation within the housing 10, and the follower shoulders 32 and 33 bearing against the packing element shoulders 34 and 35. This particular relationship of the parts is emphasized somewhat as it is through the proper spacing of the attaching ears and the use of elongated fastening means such as the bolts 20 and 21 that the stuffing box is enabled to efficiently absorb and withstand the wear produced by the relative lateral movement of the parts resulting from the sidewise movement of the polish rod 17 caused by the conventional walking beam (not shown).

As best shown in Figs. 2 and 5, the packing element 11 is novel both as regards its internal construction and its external configuration. This packing element comprises a series of alternate layers of resilient material 36, such as synthetic rubber or the like, open mesh fabric, 36', and filaments 36'' of cotton, rayon or the like formed by wrapping a ribbon of such materials in successive layers about a spindle and molding it into a unitary structure by the application of heat and pressure. The finished product, as indicated in the drawings, has a series of such filament layers extending diagonally downward towards the polish rod forming a wearing surface which is not easily broken down and which maintains a firm sealing surface 37 and sharp sealing lip or edge 38 despite wear and corrosion.

The body of the packing element 11 comprises a downwardly and inwardly tapering upper portion 39 and a substantially hemispherically curved bottom 40, the housing 10 being similarly shaped for the reception of the packing element. As the packing element 11 is compressed between the housing 10 and the follower 12, this tapering and rounded bottom shape results in maintaining an efficient seal against the polish rod 17. As wear of the packing element 11 inevitably occurs, the seal is maintained by tightening the bolts 20 and

21 to press the packing element 11 more firmly into the housing 10 and, due to the shape of the element and the interior of the housing, efficient sealing may be maintained until the packing 11 has been largely used up, the internal construction of the packing element 11 preventing its breakdown during this wearing process.

In order to lubricate the packing element and polish rod during operations when no oil from the well reaches them and in order to reduce the fire hazard which might be occasioned by slight leakage of oil along the polish rod at times when the packing element 11 does not maintain a perfect seal, the follower 12 is provided with a lubricating chamber 41 surrounding the polish rod 17. As best shown in Figs. 3 and 4, the upper portion of the follower 12 is formed with a plurality of spaced inwardly projecting upper and lower retaining lugs 42 and 43, respectively, between which an annular wiper element 44 of synthetic rubber or similar resilient material is maintained. The element 44 is retained against the polish rod 17 by means of a spring 45 engaged in a notch 46 formed in the outer periphery of the wiper element 44.

An aperture 47 is formed in the side wall of the follower 12 and opens into a trough-like spout 48 extending outwardly therefrom. The spout 48 has vertical side walls 49 and 50 and an open end 51 for the discharge of oil therefrom. The floor of the spout 48 is formed at two horizontal levels 52 and 53, the top level 52 being vertically lower than the top surface 54 of the lower retaining lugs 43. By this arrangement it is possible to supply lubricating fluid to the chamber 41 by admitting it to the lower spout level 53 so that it will drain into the chamber 41 rather than out the open end 51 of the spout. At the same time, it will be noted that the bottom edge of the wiper element 44 will at all times lie above the top floor level 52 of the spout and consequently above any fluid within the chamber 41, so that any oil which has leaked past the packing element 11 into the chamber 41 cannot by-pass the wiper element 44 but will be stripped from the polish rod 17 and collected in the chamber 41 to be ultimately discharged through the open end 51 of the spout into a suitable receptacle.

For ease in assembling the stuffing box, the packing element 11 may be provided with a diagonal split 55 and a similar split 56 typically may be formed in the wiper element 44. The wiper element 44 may be inserted through the aperture 47 and wrapped about the polish rod 17, whereas the spring 45 may be inserted through an annular aperture 57 located in the top of the follower 12 and formed by cutting away a portion of the upper retaining lugs 42.

The operation of the apparatus will be more or less obvious from the foregoing description. The tapered construction of the packing 11 and the corresponding shaping of the inner surface of the casing 10 is such that as wear occurs incident to reciprocation of the rod 17, the packing 11 tends to be moved bodily radially inwardly. Accordingly, throughout the life of one of the packings 11, a snug fit thereof with the polish rod is constantly maintained. The fabrics and filaments embedded in the packing 11, in combination with the sharp lower edge 38 of the packing, serves to wipe down the rod 17 during each upward movement thereof. Accordingly the passage of oil past the rod 17 is minimized.

The bolts 20 and 21 have slight clearance in

the openings through which they pass, and since the lugs 18 and 19 are always substantially spaced above the lugs 26 and 27, a reasonable degree of lateral deflection of the packing ring 44 relative to the packing 11 is provided for. Even when the follower 12 is in its lowermost position as shown in Figure 1, with the packing 11 substantially completely worn, the length of the bolts 20 and 21 between the casing and follower is sufficient to permit the lateral movement 10 referred to.

The reservoir 41 serves to maintain a body of lubricant above the packing 11. Without this packing, or with an inefficient packing, an excessive amount of oil moves upwardly along the 15 rod 17. Even with the most efficient packing, as in the present construction, some small quantity of oil finds its way above the packing. In the present construction, the reservoir 41 serves to contain this leakage oil to assist in lubricating the rod 17.

Because of the extremely high efficiency of the present construction, particularly when the bolts 20 and 21 are maintained properly tight, insufficient oil for lubrication purposes sometimes finds its way into the chamber 41. Additional oil may be added by pouring it onto the surface 53. Excessive oil cannot be maintained in the reservoir 41, however, either by pouring oil thereinto in the manner stated or through the accumulation of leakage oil, since an excess of the lubricant will overflow over the surface 52. The level of the lubricant accordingly will always be maintained below the bottom of the packing ring 44.

I claim:

1. A polish rod stuffing box comprising a generally cup-shaped apertured housing having a downwardly and inwardly tapering interior side wall terminating in a concave substantially hemispherically curved bottom portion, a pair of apertured ears projecting laterally outward from said housing, an apertured resilient packing element in said housing having its outer surface shaped to conform to the interior wall of the latter and including a pair of horizontal shoulders formed in its top portion, a follower having its bottom portion shouldered to conform to the top portion of said packing element and adapted to abut against the latter, means forming a lubrication chamber within said follower including an outlet in the side wall thereof, a radially inwardly spring-pressed, annular wiper within said chamber above said outlet, a pair of apertured ears extending laterally outward from said follower, and fastening means operatively associated with both said pairs of ears for adjusting the pressure exerted on said packing element by said housing and follower.

2. A polish rod stuffing box comprising a generally cup-shaped apertured housing having a downwardly and inwardly tapering interior side wall terminating in a concave substantially hemispherically curved bottom portion, a pair of apertured ears projecting laterally outward from said housing, an apertured resilient packing element in said housing having its outer surface shaped to conform to the interior wall of the latter, a follower having its bottom portion shaped to conform to the top portion of said packing element and adapted to abut against the latter, means forming a lubrication chamber within said follower including an outlet in the side wall thereof, an annular wiper within said chamber above said outlet, a pair of aper-

tured ears extending laterally outward from said follower, and fastening means connected between said pairs of ears for adjusting the pressure exerted on said packing element by said housing and follower.

3. A stuffing box comprising a generally cup-shaped, apertured housing having a downwardly and inwardly tapering interior side wall terminating in a smoothly curved, substantially hemispherical bottom portion, said curved bottom portion lying wholly above a plane perpendicular to the axis of said stuffing box and passing through the radially inner limits of said curved bottom portion, a pair of apertured ears projecting laterally outward from said housing, an apertured resilient packing element in said housing having its outer surface shaped to conform to the interior wall of the latter and including a pair of horizontal shoulders formed in its top portion and an intermediate portion tapered to decrease in diameter downwardly, a follower having its bottom portion shouldered to conform to the top portion of said packing element and adapted to abut against the latter, means forming a lubrication chamber within said follower including an outlet in the side wall thereof, a pair of apertured ears extending laterally outwardly from said follower, and fastening means connected between said pairs of ears for adjusting the pressure exerted on said packing element by said housing and follower.

4. A stuffing box comprising a housing having a downwardly and inwardly tapering interior side wall terminating in a concave smoothly curved bottom portion, said curved bottom portion lying wholly above a plane perpendicular to the axis of said stuffing box and passing through the radially inner limits of said curved bottom portion, a pair of apertured ears projecting laterally outward from said housing, an apertured resilient packing element in said housing having its outer surface shaped to conform to the interior wall of the latter and including a pair of horizontal shoulders formed in its top portion and an intermediate portion tapered to decrease in diameter downwardly, a follower having its bottom portion shouldered to conform to the top portion of said packing element and adapted to abut against the latter, means forming a lubrication chamber within said follower, a pair of apertured ears extending laterally outward from said follower, and fastening means connected between said pairs of ears for adjusting the pressure exerted on said packing element by said housing and follower.

5. A stuffing box comprising a housing having a downwardly and inwardly tapering interior side wall terminating in a smoothly curved bottom portion, said curved bottom portion lying wholly above a plane perpendicular to the axis of said stuffing box and passing through the radially inner limits of said curved bottom portion, an annular packing element in said housing, the outer surface of which conforms to the shape of said interior housing wall, and the top portion of which includes a pair of horizontal shoulders and an intermediate portion tapered to decrease in diameter downwardly, a follower having its bottom portion shouldered to conform to the top portion of said packing element and adapted to abut against the latter and to nest within said housing, and fastening means 70 interconnecting said housing and said follower

and adjustable to control the amount of pressure exerted on said packing element.

6. In a polish rod stuffing box, a packing follower comprising a generally cylindrical, hollow body having a lubrication chamber formed therein and top and bottom central apertures for the passage of a polish rod therethrough, a pair of apertured attaching ears extending laterally outwardly at opposite sides of the top portion of said body, a plurality of spaced upper and lower retaining lugs projecting radially inwardly into the upper portion of said chamber, an annular radially inwardly spring-pressed wiper element in said chamber between said upper and lower lugs, the side wall of said body having an aperture adjacent said lower lugs, and a spout extending outwardly from said last mentioned aperture having its trough floor at two levels, the top level being lower than the upper surface of said lower lugs.

7. In a polish rod stuffing box, a packing follower comprising a hollow body having a lubrication chamber formed therein and top and bottom central apertures for the passage of a polish rod therethrough, a plurality of spaced upper and lower retaining lugs projecting radially inwardly into the upper portion of said chamber, an annular radially inwardly spring-pressed wiper element in said chamber between said upper and lower lugs, the side wall of said body having an aperture adjacent said lower lugs, and a spout extending outwardly from said last mentioned aperture and having its trough floor at two levels, the top level being lower than the upper surface of said lower lugs.

8. In a stuffing box, a packing follower comprising a hollow body having a lubrication chamber formed therein, a plurality of spaced upper and lower retaining lugs projecting radially inwardly into the upper portion of said chamber, an annular wiper element in said chamber between said upper and lower lugs, the side wall of said body having an aperture adjacent said lower lugs, and a spout extending outwardly from said last mentioned aperture and having its trough floor at two levels, the top level being lower than the upper surface of said lower lugs.

9. A stuffing box comprising a housing having its interior side wall tapering downwardly and inwardly and terminating in a smoothly curved bottom portion, an annular packing element in said housing, the outer surface of which conforms to the shape of said interior housing wall, a follower adapted to abut against said packing element and to nest within said housing, said packing element comprising a plurality of layers of filaments embedded in a resilient material and extending diagonally downward from said outer surface toward the center thereof at a greater angle to the vertical than the taper of said side wall.

10. A stuffing box comprising a housing having an interior side wall portion tapering to decrease in diameter downwardly and terminating in a smoothly radially inwardly and downwardly curving bottom portion, said curved bottom portion lying wholly above a plane perpendicular to the axis of the stuffing box and coincident with the radially inner limits of said curved bottom portion, an annular packing element in said housing, said packing element having its outer surface conforming in shape to said interior housing wall, said packing element having embedded therein layers of elasticity-reducing material, said layers being conical and taper-

ing downwardly and inwardly at a sharper angle than the taper of said housing side wall portion, and a follower adapted to abut the top of said packing element to force it relatively downwardly.

11. A stuffing box constructed in accordance with claim 10 wherein said layers of material are alternately filaments and fabric.

12. A stuffing box comprising a housing having an interior side wall portion tapering to decrease in diameter downwardly and terminating in a smoothly radially inwardly and downwardly curving bottom portion, said curved bottom portion lying wholly above a plane perpendicular to the axis of the stuffing box and coincident with the radially inner limits of said curved bottom portion, an annular packing element in said housing, said packing element having its outer surface conforming in shape to said interior housing wall, said packing element having embedded therein layers of elasticity-reducing material, said layers being conical and tapering downwardly and inwardly at a sharper angle than the taper of said housing side wall portion, and a follower having its longer end adapted to abut said packing element, the lower end portion of said follower having a surface generally perpendicular to the axis of the said packing element and a surface tapering to decrease in diameter downwardly, the upper end of said packing element having portions corresponding in shape to and engaging said lower end surfaces of said follower to exert downwardly and radially outward forces against the upper end portion of said packing element.

13. A stuffing box for a rod comprising a housing having an interior side wall portion tapering to decrease in diameter toward one end of the housing and terminating in a smoothly curved portion formed substantially accurately as a section of a sphere, said end of said housing having an opening through which the rod projects and such opening being of larger diameter than the rod, a packing element corresponding generally in external shape to the interior wall of said housing and arranged therein, and a follower connected to said housing and arranged at the other end thereof and having an end engaging said packing element, said follower having an opening through which said rod extends and such opening being of larger diameter than the rod, said end of said follower having a shoulder engaging a portion of said packing element to transmit direct axial movement thereto and having a portion tapered to decrease in diameter toward said first-named end of said housing and engaging a portion of said packing element to exert radially outward forces on the adjacent portion of said packing element while said shoulder exerts endwise force thereagainst, said packing element having an opening therethrough corresponding in size to the rod snugly to fit the latter and the portions of the upper end of said packing element which are engaged by said follower corresponding in shape to the follower surfaces which they engage.

14. A stuffing box constructed in accordance with claim 13 wherein said packing element has imbedded therein layers of elasticity-reducing material, such layers of material being conical and tapering to decrease in diameter toward said first-named end of said housing at an angle sharper than said tapered wall portion of said housing.

15. A stuffing box packing element comprising

a resilient annular body having a longitudinal aperture therethrough of substantially uniform cross-section and including a downwardly and inwardly tapering exterior surface terminating in a convex smoothly curved bottom portion, said body comprising alternate layers of fabric and filaments embedded in a resilient material.
